ATTORNEYS

UNITED STATES PATENT OFFICE.

DE VERN CLAYTON HUFFMAN, OF ST. LOUIS, MISSOURI.

PRINTING DEVICE.

1,262,195.

Specification of Letters Patent.

Patented Apr. 9, 1918.

Application filed April 12, 1917. Serial No. 161,543.

To all whom it may concern:

Be it known that I, DE VERN C. HUFFMAN, a citizen of the United States, and a resident of St. Louis, in the State of Missouri, have invented new and useful Improvements in Printing Devices, of which the following is a specification.

My invention is an improvement in sales slips, and has for its object to provide mechanism of the character specified adapted for the use of merchants, shop keepers, market-men and the like, wherein means is provided for entering the various items of a sales slip in printed characters on the slip, and wherein in the total of the printed items is presented at the close of the operation, in order that it may be entered on the slip.

In the drawings:

Figure 1 is a top plan view of the machine, with parts in section;

Fig. 2 is a section on the line 2—2 of Fig. 1, looking in the direction of the arrows adjacent the line;

Figs. 3 and 4 are sections on the lines 3—3 and 4—4, respectively, of Fig. 2, each view looking in the direction of the arrows adjacent the line;

Fig. 5 is a partial top plan view;

Fig. 6 is a plan view of the completed sales slip;

Fig. 7 is a section through the register number wheels;

Fig. 8 is a section on the line 8—8 of Fig. 7, looking in the direction of the arrows adjacent the line.

The present embodiment of the invention is adapted for coöperation with sales slips indicated at 1 in Fig. 6, and the machine comprises a suitable supporting plate 2 which is adapted to rest upon the pad of slips, as shown in Figs. 1 and 2. At the right of the plate a series of number wheels 3 is mounted, the said wheels being four in number in the present instance, and the wheels are mounted upon shafts 4, which are journaled in the arms 5 of yoke shaped springs, the bodies 6 of the springs being secured to the plate in the manner shown in Figs. 2 and 3. These spring plates 5—6 normally hold the wheels spaced above the surface of the pads, the plate 2 being cut away beneath the wheels, as shown in Fig. 2, in order that when the wheels are depressed in a manner to be presently described, the numerals on the peripheries of the wheels will be brought into contact with the pads.

An inked ribbon 7 is arranged beneath the number wheels, the said ribbon being mounted at its ends on reels 8, and the reels are journaled upon spindles 9 connected with the 60 plate. The ribbon passes beneath guide pins 10 extending outwardly from the plate, and each number wheel has secured thereto a gear wheel 11, which is adapted to be engaged by operating mechanism to be later 65 described. A cover 12 is arranged above the number wheels, and the cover is cut away at the end adjacent the number wheels. It will be noted, upon inspection of Fig. 4, that each number wheel has raised characters on 70 its periphery, and the said characters are printing characters which will print upon the slips 1 when the individual number wheels are depressed to bring the numerals into contact with the inked ribbon. The 75 number wheels are rotated by means of teeth on one of the side walls of substantially U-shaped members 15. These members 15 fit over the number wheels, as shown in Figs. 2 and 4, the rack teeth engaging the pinions in 80 such manner that the wheels will be turned when the U-shaped members are moved longitudinally, and the number wheels will be depressed when the U-shaped members are 85 held in normal position, and returned to normal position when released, by means of coiled springs 16 which are arranged between the U-shaped members and a cross pin 17 connecting with the cover 12.

The teeth are engaged by angular lugs 18 on spring arms 19 which are secured to the plate, said arms pressing the angular portion 18 against the teeth. Each of the U-shaped members is provided in its upper portion or 95 body with a series of notches or openings 20, and adjacent each opening is a numeral, as shown in Fig. 1. These openings 20 are adapted to be engaged by the finger nail, or pencil point, to move the U-shaped members 100 or plungers in a direction to operate the printing number wheels. The angular portions 18 are, in effect, pawls, for preventing overthrow of the number wheels and to indicate to the operator how many notches or 105 teeth have been passed over.

A second series of number wheels 21 is arranged at the opposite side of the plate from the number wheels 3, each number wheel bearing numerals on its peripheral surface, 110 the said numerals running from "0" to "9". These number wheels are arranged upon a

shaft 22, which is journaled in the cover 12, and is provided at its outer end with a knob or handle 23 for convenience in rotating the shaft. The shaft, as shown in Figs. 7 and 8, 5 has a longitudinally extending groove 24, and each number wheel has a spring-pressed ball 25, which is adapted to engage in the groove to lock the number wheel to the shaft. These balls are arranged in radial recesses 26 10 in the wheels, the spring 27 being between the balls and the bottom of the recess. The groove is so cut that while the wheels may, rotate freely in one direction with respect to the shaft they cannot rotate in the opposite 15 direction, the ball acting as a clutch.

Each of the U-shaped members 15 is provided at the end adjacent the number wheels 21 with a longitudinally extending rack bar 28, and each of these rack bars 20 engages the teeth of a pinion 29 rigid with the adjacent number wheel. Thus it will be obvious that whenever one of the number wheels 3 is moved by the U-shaped member coöperating therewith the corresponding 25 number wheel 21 at the opposite side of the plate will be also moved.

Each pinion 29 engages a gear wheel 30 which is journaled on a shaft 31 below the shaft 22 and each number wheel on the opposite side from the pinion 29 is provided with a single tooth 31, which is adapted to engage the adjacent gear wheel once during each complete rotation of the number wheel, to cause the tooth to operate the gear wheel 35 to move the succeeding number wheel a distance of one tooth. Thus the units wheel of the series 21 has a tooth 31 and pinion 29. The tens wheel has both pinion and tooth, as does also the hundredths wheel. The 40 thousandths wheel, however, has only the pinion and no tooth. When the units wheel of the series 21 has been moved a complete rotation, the tooth 31 of the said wheel will engage the gear wheel 30 engaging the pinion 29 of the tens wheel, and will cause the said gear wheel 30 to move the tens wheel a distance of one tooth or one numeral. The cover 12 is provided with an opening 32 at each number wheel of the series 21, and 45 these openings, being in alinement, will give the total, the numerals forming the total appearing at the openings.

In operation, the device being in place on the pad of sales slips in the manner shown 50 in Figs. 1 and 2, an entry is written in in pencil, as, for instance, "1 bu. potatoes." With the pencil or the finger nail the book-keeper or salesman now sets the number wheels of the series 3 to print the cost of 55 the bushel of potatoes, as, for instance, "\$2.50". The units wheel already stands at "3", so no manipulation of the units wheel is necessary except to depress the same to cause it to print. The operator now places 60 the pencil or his finger nail in the notch of

the hundredths wheel operating member 15 and draws the operating member toward himself, until the pencil or finger nail engages the cut away edge of the cover. He then depresses the type wheel to cause the 70 same to print. He next places the pencil in the notch in the tens wheel indicated by the numeral 3 and draws the said member toward himself until the pencil engages the stop formed by the edge of the cover, after 75 which he depresses the wheel to cause the same to print. The number wheels of series 3 and 21 both register now "\$2.50", and this amount is printed on the sales slip in alinement with the notation "1 bu. potatoes", by the number wheels of series 3, and the numerals "\$2.50" appear at the openings 32. Each succeeding entry is printed in the same manner, and when the slip has been completed, as shown in Fig. 6, the total 80 of the entered items will appear at the openings 32. This total is written in below the cost of the various items, and the sales slip is complete.

In order to reset the number wheels of 90 series 21, the knob or head 23 is used. The teeth of the element 28 are ratchet teeth, so that when the operating member 15 is moving in a direction to operate the number wheels 3 the number wheels 21 will also be 95 operated, but when the member is moving under the influence of the spring 16 the teeth will slip idly over the teeth of the pinion. The springs 19 lift the members 15 during the return movement under the influence of the spring 16, so that they do not affect the number wheels. 100

I claim:

1. A device of the character specified, comprising a plate, a series of coaxial number wheels, a mounting for each wheel connected with the plate, said wheels being supported beyond the edge of the plate, each mounting being resilient and normally pressing the wheel upward above the level 105 of the plate, each wheel having a pinion rigid therewith, an operating member for each wheel, each member being substantially U-shaped and having one side wall provided with rack teeth for engaging the pinion, a spring normally holding the teeth of each operating member out of engagement with the teeth of the pinion, a spring 110 for returning each operating member. 115

2. A device of the character specified for 120 use with sales slips and to be moved there-over, comprising a plate one edge of the plate being adapted to form a guide for the entering of entries on the slip, a series of printing wheels at the said edge and extending beyond the edge to print in line with the item entered, an independent resilient mounting for each printing wheel and normally holding the wheel in elevated position, and operating means for each print- 125 130

ing wheel for depressing the printing wheel and mounted to reciprocate, and spring controlled to normal position and independent of the operating means for the other wheels.

5 3. A device of the character specified for use with sales slips comprising a plate adapted to rest upon the slip and to be moved thereover, one edge of the plate being adapted to form a guide for the entering of entries on the slip, a series of printing wheels at the said edge and extending

beyond the edge to print in line with the item entered, and operating means for each printing wheel and for depressing the printing wheel and mounted to reciprocate, and spring controlled to normal position, and independent of the operating means for the other wheels. 15
